DESIGN FOR A BOOK WITH BOX COVERS

Benjamin F. Jay, New York, N. Y.

Application April 18, 1942, Serial No. 106,614

Term of patent 14 years

To all whom it may concern:

Be it known that I, Benjamin F. Jay, a citizen of the United States, residing in the city, county, and State of New York, have invented a new, original, and ornamental Design for a Book With Box Covers, of which the following is a specification, reference being had to the accompanying drawing, forming a part thereof, in which:

Fig. 1 is a plan view of a book with box covers, showing my new design, the same shown in open

position with the leaves in standing position for purposes of illustration;

Fig. 2 is an end elevational view thereof; and

Fig. 3 is a top perspective view thereof in closed position.

I claim:

The ornamental design for a book with box covers, as shown.

BENJAMIN F. JAY.
